STEAM TRAP

Filed Oct. 27, 1926

Inventor:
James Logan Flits
By Mr. H. W. D.
Attorney.

UNITED STATES PATENT OFFICE

JAMES L. FITTS, OF MERCHANTVILLE, NEW JERSEY, ASSIGNOR TO WARREN WEBSTER
& COMPANY, A CORPORATION OF NEW JERSEY

STEAM TRAP

Application filed October 27, 1926. Serial No. 144,448.

The object of my invention is to provide an efficient construction of condensation steam trap adapted to operate under high pressure for permitting the passage of water of condensation but restricting or preventing the passage of steam.

My improvement has a further object, namely, to provide a construction of the hollow thermostatic member or members, for use singly or in tandem within a suitable casing, and wherein the member is built up of flexible diaphragms and rigid annular portions mechanically connected by clamped soldered joints, to provide flexibility from the hub portion to the perimeter and thereby secure the desired elasticity with a minimum diameter to the expansible member.

The invention has for a further object the obtainment of a large movement to the valve member from thermostatic elements of relatively small diameter adapted for use with steam at medium and high pressures, even to one hundred pounds, and corresponding temperature, approximately 328° F. without danger of collapsing.

A still further object is to form the structure of the thermostatic member of metals capable of maintaining elasticity under high pressure and temperature and the port controlling means of non-rustable alloy, such, for example, by use of sheet Monel metal (alloy of copper and nickel) for the flexible disks, brass for the hub portions, and rustless steel (chrome iron alloy) for the seat and valve piece, whereby efficient operation and durability are assured.

With the foregoing and other objects hereinafter stated in view, my invention consists of certain improvements in steam traps fully described in the following specification and pointed out in the claims.

Referring to the drawings: Fig. 1 is a vertical section of a steam trap embodying my invention; Fig. 2 is an enlarged vertical section of my improved thermostatic structure removed from its casing; Fig. 3 is a plan view of the thermostatic structure embodying my improvements when removed from its casing; Fig. 4 is a cross section of the disk member of Fig. 3 taken on line 4—4 thereof;

Figs. 5 and 6 are cross sections of modifications; and Fig. 7 is a modification of the thermostatic member.

The present invention is an improvement upon the general type of trap described in Letters Patent of the United States No. 1,235,673, granted to me on August 7, 1917, wherein the thermostatic disk members were formed of diaphragm disks of sheet metal having their perimeters united by an annular joint formed of a double folded seam occupying a large portion of the diameter and area of the disk. In the present invention, all interfolded seams are eliminated and an efficient simpler construction employed.

Referring to Fig. 1, the body or casing 2 may be of any form desired but is shown of a form well suited to my improved thermostatic vapor expansion element, and is provided with a side inlet 3 and a bottom outlet 4, the latter having a valve seat preferably formed of rustless metal such as chrome-nickel iron alloy or chrome steel alloy, which efficiently resists abrasion due to "wire drawn" condensation discharge. By employment of these rustless alloys, not only is the abrasion prevented owing to the non-rusting qualities of the same, but the smoothness of the valve seat is maintained and permits free discharge with a minimum opening by the thermostatically operated valve. The upper portion of the valve body is closed by a bonnet or cap 9 screwed thereon at 10 and providing access to the interior thereof for practically its entire area. 8 is a sheet metal disk having a diameter somewhat greater than the interior of the body so that its perimeter rests in an annular groove in the annular rim of the body, as shown in Fig. 1. Interposed between the perimeter of the disk 8 and the bonnet 9 is a ring washer preferably of the copper-asbestos gasket type, the same forming a steam tight joint over the junction of the disk perimeter and edge of the annular depression as definitely shown at 2a in Fig. 1. The disk 8 is provided with a central hole and also with one or more holes 8a to permit equalization of pressure above and below the disk. The thermostatic vapor

expansion element 7 is provided with a valve piece 6 at the bottom for controlling the thoroughfare or discharge opening through the seat 5 and has at the top an upwardly extending threaded nipple 29 which extends through the central orifice in the disk 8 and is secured therein by clamping nut 30. In this manner, the thermostatic element is definitely supported and the distance between the said support and the discharge orifice positively assured, which facilitates greatly in the assembly.

Referring more particularly to the thermostatic element removed from the body or casting and, as illustrated, on an enlarged scale in Fig. 2, the following features of construction are specially noted: As shown, the element 7 is composed of two thermostatic disk members 7a and 7b connected together and having their respective expansion chambers 12, 12, in communication with each other and operating as a whole like a bellows type of expansion element. Then the disk members 7a and 7b are each constructed in the following manner, namely, a heavy annular ring like rim 15 of brass having two beaded outer edges 16 constitutes the perimeter of the expansible element and two flanged flexible disk shaped plates 13, oppositely flanged as at 14, are respectively placed over opposite sides of the ring like rim and rolled tightly over the respective bead like rim portions 16 and soldered rigidly in position as shown at 17, the solder being sweated in to insure a better union. This joint constitutes a mechanical joint as the disks are, in effect, hooked upon the bead like portions 16 and this mechanical joint is strengthened and made tighter by the soldered union 17 between the disk members 13 and between them and the ring member 15. To insure maximum flexibility of the plates 13, they must not be attached to the top and bottom of the ring member 15 and to insure their freedom of movement, the top and bottom annular walls of the ring member 15 are beveled inwardly as at 18 to provide a clearance between said parts and the plates 13. In this way, the flexibility of the plates extend to the bead like portions 16 of the ring like members 15 and hence for their full diameters. The central portions of these disk like plates 13 are provided with apertures, preferably of the same diameter. Where there are two expansible elements to be connected as shown and with their vapor chambers 12, 12, in communication, the joint is made by an interposed ring or washer 20 through which and over the same and disk members 13 is placed a tubular part 21 which is then expanded and swaged down at 22, similar in function to the well known grommet used to fasten canvas or other substances together. The joint is then soldered at S to make it gas tight. In respect to the hub 23 which carries the valve

piece 6, this hub is provided with a neck 25a which snugly fits the hole in the lowermost plates 13, which is clamped between a shoulder 23b of the hub 23 and a ring piece 24 having a beveled recess 24a over which the annular flange of the neck is expanded or swaged over the ring piece as at 25. This joint is likewise soldered at S. The valve piece 6 is screwed into the hub 23 and when in proper adjustment therein, it is pinned in permanent position by transverse pin 6a. Secured to the uppermost disk member 13 adjacent to its central opening is a hub 26 having its inner annular rim flanged or swaged as at 28 over a ring or washer 27 placed on the inner face of the disk plate 13, said construction being similar to that described in connection with the hub 23 and lowermost disk plate 13. Similarly, also this hub joint is soldered as at S. As before pointed out, this hub portion 26 is provided with the screw threaded nipple which extends through the central hole in the plate 8 and clamped thereto by nut 30. It is pointed out that where the parts 25 and 28 are formed as straight studs and are riveted over washers having straight holes, it has been impossible to make non-yielding joints and hence caused undesirable strains to come upon the soldered joints at S. By making the parts 25 and 28 annular and expanded and upset within a conical aperture in the nuts 24 and 27, the metal portions of the parts 25 and 28 are disturbed throughout their mass and become set and tight, so that no strain comes upon the soldered joints and leakage of gas is thereby avoided. It will also be seen that a tapered charging hole 31 extends through the hub piece 26 and by which air and a volatile fluid are admitted to the communicating expansion chambers 12, 12; said hole thereafter being sealed with a tapered plug 32, and preferably soldered in position. The fluid to be volatilized may be alcohol or any other fluid adapted to be vaporized by steam heat, many of which are well known for use in thermostatic traps for steam heating systems.

In the making of the thermostatic element, the two middle disk plates 13 are united together at their central portions before their flanged perimeters 14 are secured to the beaded portions of the ring shaped rims 15. Further, the top and bottom plates 13 are first secured to their respective hubs 26 and 23 and thereafter their flanged perimeters 14 are secured to the beaded portions of the ring shaped rims 15. This procedure enables all of the unions and joints to be easily made and gas tight. The soldered joints S are sweated in so as to give the greatest security against vapor leakage and to strengthen the union as at the perimeter portions 17.

It will be understood that the thermostatic element may be formed in one or more of the expansible chambers 12, two such being shown

by way of example. It is manifest, however, that so far as my invention is concerned, one of said chambers alone will suffice, such for example, as if the hub 23 and its valve piece 5 were connected directly to the plate 13 second from the top (Fig. 7), the number of expansible chambers employed being only for the purpose of providing adequate movement of the valve piece to suit the special 10 uses of the device. It will be evident that the disk or diaphragm plates 13 are flexible from the center hubs out to the curve of the flanged edges where they are united to the rim beads 16.

15 I have found that flat plates and those having annular corrugations will in time assume a permanent bulged or arched form which brings about a change in their elasticity and a change in the valve movement to and from 20 the seat. To overcome this, I have provided a series of radial grooved or depressed portions located either upon the inside (Figs. 2 and 4) or outside (Fig. 5) of the disk surfaces or part outside and part inside (Fig. 6), 25 said construction preventing to a very large degree the objectionable bulging by throwing the flexure into that area near the outer edge, and yet by their form and shallow depth permit flexure more or less over the whole plate area and elimination of sharp or excessive bending at either center or outer portions. I have shown these radial portions at 30 19 in Figs. 2, 3, 4, 5 and 6.

35 While I have referred to the joints between the mechanically connected part being soldered at S, nevertheless, it is desirable that the surfaces shall be first tinned before assembled and the solder applied.

40 While I have shown in Fig. 2 the two thermostatic elements 12, 12, with their interior chambers in communication through the tubular union or part 21, it is to be understood that this communication is not essential because the several thermostatic elements may 45 be made as indicated in Fig. 7 and the screw threaded hub 29 of one element may be screwed into the internally screw threaded hub 23, so that two or more of such elements may be coupled together with the uppermost 50 screw threaded nipple 29 attached to the suspension plate or disk 8 while the valve piece 6 would be attached to the lowermost hub 23. In this arrangement, each one of the thermostatic elements would operate as separate expansive means and the amount of movement which would be given to the valve piece would be the same as the total of the movements of 55 the several elements.

60 It will now be apparent that I have devised a novel and useful construction which embodies the features of advantage enumerated as desirable, and while I have in the present instance shown and described the preferred embodiment thereof which has been found in 65 practice to give satisfactory and reliable re-

sults, it is to be understood that I do not restrict myself to the details, as the same are susceptible of modification in various particulars without departing from the spirit or scope of the invention.

Having now described my invention, what I claim and desire to secure by Letters Patent is:

1. A thermostatic expansive element having two flexible disk shaped walls of sheet metal whose perimeters are oppositely curved in the form of beads and said beaded perimeters spaced apart and out of contact, combined with an annular non-flexible rim portion having its perimeter formed with parallel ribs semi-circular in cross section formed on the rim portions over which the curved perimeters of the sheet metal walls loosely extend but closely fit and by which they are self-locked in definitely spaced relation, and a soldered union between the separated beaded edges of the two flexible walls and the perimeter of the rim intermediate of its two semi-circular rib portions, the non-flexible rim forming the sealed perimeter of the expansive element.

2. The invention according to claim 1, wherein further, the flexible walls are provided with a large number of small radial ribs of substantially uniform depth, said ribs 95 entirely separate from each other and beginning adjacent to the nonflexible rim portion and terminating at a distance from the center to increase the resistance to bending in radial directions at substantially all points 100 intermediate of the circumferential beginning and ending of the rib portions.

In testimony of which invention, I hereunto set my hand.
